DUSTER

Filed Feb. 26, 1927

Donald Edwin Greene

Inventor

UNITED STATES PATENT OFFICE.

DONALD EDWIN GREENE, OF DECATUR, ILLINOIS.

DUSTER.

Application filed February 26, 1927. Serial No. 171,246.

This invention relates to dusters adapted for cleaning and polishing the surfaces of automobile bodies, furniture and other articles on which the finish is liable to be 5 scratched or otherwise marred by the use of wiping cloths which may be compressed into such a compact body that sand or particles of gritty matter that lodge on the wiping cloth are brought into forcible contact with 10 the surface being cleaned or polished.

One form of duster heretofore extensively used consists of a bundle of yarn comprising a large number of strands of uniform length secured together at their middle point by 15 means of stitches or other fastening device. The disadvantage of this form of duster resides in the fact that after slight usage the strands become matted into such a compact body as to render the duster unsuited for 20 wiping a varnished or polished surface.

One of the objects of my invention is to provide a duster constructed of yarn which will possess a loose, fleece-like body that will retain its softness after much usage.

25 Another object of my invention is to produce a duster that may be easily compressed into a suitable form for dusting purposes when grasped by the hand.

The details of my improved duster are 30 shown in the drawings accompanying this application in which—

Fig. 1 is a plan of my complete duster.

Fig. 2 is an end view.

Fig. 3 is a perspective view showing the 35 duster grasped in a hand.

Fig. 4 is a view of one of the strands of 40 yarn after it has been kinked.

Fig. 5 is a view of one of the strands drawn to the same scale as Fig. 4, and showing the 45 strand before kinking.

Referring to the drawings, it will be seen that my improved duster is similar in general construction to other yarn dusters heretofore used. The novel feature in the 45 construction of my duster resides in the kinking of each strand of the yarn of which it consists.

As shown in Figs. 1 and 2 a suitable number of the kinked strands 10 are assembled 50 together into a bundle 11 and stitched across the middle as indicated at 12, thus dividing the bundle into two sections 13 and 14, each section flaring outwardly toward the end

into a fleece-like body. The kinking and consequent shortening of the strands increase 55 their diameter several times and impart to each strand a considerable degree of resiliency by reason of which properties the outer ends of the sections 13 and 14 are formed into enlarged dusting surfaces which 60 are very loose and elastic.

In use, the duster is grasped across the middle stitched portion and the two sections 13 and 14 compressed together, thus presenting to the surface to be dusted or polished 65 a large fleecy body which, because of its great elasticity, may be pressed against the surface with sufficient firmness to remove dust or other foreign matters without danger 70 of marring the finish of the article being cleaned.

My improved duster may be treated with suitable oils or cleaning solutions in the same manner as with other dusters of this character to increase its effectiveness as a cleaning 75 device, but this facility forms no part of my invention.

From the foregoing description it will be seen that I have produced a yarn duster in which a smaller number of strands may be used, because of the enlarged mean diameter of the strands effected by kinking, than is required in dusters constructed of straight strands, to produce a dusting surface of 80 equal size.

It will be observed also that the elasticity of my duster precludes the possibility of the strands being compressed into a compact body, and renders the duster easy and 85 pleasant to grasp.

In kinking the strands of yarn, I preferably accomplish this object by knitting a continuous length into tubular formation and then unraveling and cutting the strands into even lengths, although it is to be understood that I may adopt other suitable methods of 90 kinking the yarn.

Having described my invention, I claim:— A yarn duster of the class described, consisting of a bundle of yarn in which the 95 separate strands are formed with a series of evenly spaced sinuous kinks throughout their entire length.

In testimony whereof I have hereto affixed my signature.

DONALD EDWIN GREENE.
